UNITED STATES PATENT OFFICE.

LAWRENCE W. LUellen, OF MOUNTAIN LAKES, NEW JERSEY, ASSIGNOR, BY MESNE ASSIGNMENTS, TO INDIVIDUAL DRINKING CUP COMPANY, INC., A CORPORATION OF NEW YORK.

CUP-DISPENSER.

1,337,843.

Specification of Letters Patent. Patented Apr. 20, 1920.

Application filed July 2, 1914. Serial No. 348,534.

To all whom it may concern:

- Be it known that I, LAWRENCE W. LUellen, a citizen of the United States, residing in Mountain Lakes, county of Morris, and 5 State of New Jersey, and whose post-office address is Boonton, New Jersey, have invented certain new and useful Improvements in Cup-Dispensers, of which the following is a specification.
- 10 This invention relates to dispensers for individual drinking cups of paper or the like, of the type described and claimed broadly in my Patent No. 1,043,853. The present application also shows an apparatus 15 embodying certain features which are claimed in my pending application Serial No. 616,714, filed March 24, 1911, and to which features, therefore, no claim is made herein.
- 20 The apparatus of the present invention is designed to have stored within it a stack of nested cups which are fully protected thereby from dust and dirt, and are thereby maintained in sanitary condition until used. It 25 includes a member which supports the stack of cups, said member having a contracted delivery opening through which the terminal cup projects into an accessible position so that it may be withdrawn from the apparatus by the user, the cups being arranged 30 so that the rim of the terminal cup is retained within the delivery opening and so protected from contamination until the cup is withdrawn for use.
- 35 The object of the present invention is to provide an improved construction for supporting the cups, whereby a stack of cups of any desired weight may be retained within the apparatus and whereby the cups may be 40 withdrawn, one at a time, with ease and certainty.
- In the accompanying drawings, which form a part of this specification,—
- Figure 1 is a front elevation of one embodiment of my invention, a part being broken away to show that the cup receiver may be of any desired length to hold such number of cups as may be convenient.
- Fig. 2 is a vertical section of the apparatus shown in Fig. 1.
- Fig. 3 is a perspective view of a slightly modified form of cup-supporting bracket.
- Figs. 4 and 5 are enlarged detail views in vertical section of a modified construction of cup dispensing ring. 55
- Fig. 6 is a similar view of another modified construction.
- Fig. 7 is a perspective view of another modified construction.
- Referring to the drawings in detail and particularly to Figs. 1 and 2:—
- Numeral 1 designates a support or back which may comprise a strip of wood and which is adapted to be secured to a wall or the like. Attached to this strip 1 is a 65 bracket 2 which comprises a supporting base 3 adapted to be secured to the strip 1 and the ring 4 which supports the cups 5 and the cup-receiving tube or magazine 6. Obviously, the manner of supporting the ring 70 4 may be modified to suit the conditions under which the apparatus is to be used. The tube 6 is preferably made of glass and closed at the top as indicated at 7. The ring 4 is preferably provided with a groove 8 75 which receives the lower end of the tube 6. If the tube 6 is long, a spring clip 9 is preferably attached to the upper part of the strip 1 so as to engage the upper part of the tube and support it in upright position. 80
- The cups 5 are preferably constructed in accordance with the invention of my Patent No. 1,032,557 having outwardly extending flanges or heads 10 about their rims, and are preferably made of paper or other cheap 85 and easily destructible substance. The paper may be coated with paraffin so as to make the cups more water-proof, if desired. These cups are nested one within the other so as to form a stack and are placed within 90 the apparatus with their open ends up. In order to support the stack of cups, the ring 4 is provided on its inner surface with a plurality of annular ribs 11 of slightly smaller inner diameter than the extreme 95 diameter of the cup flanges. The bottoms of the grooves between the ribs are preferably of slightly larger diameter than the extreme diameter of the cup flanges. In the apparatus shown in Figs. 1 and 2 the ribs 100 are spaced apart vertically distances equal to the distances between the successive cup flanges. When the stack of cups is placed in the apparatus, the flanges of one or more of the terminal cups of the stack will be engaged respectively by one or more of the ribs 105

11, which will support such terminal cups and thereby the entire stack. The lower end of the terminal cup will project a sufficient distance below the bottom of the 5 ring 4 to permit such cup to be grasped by the user and pulled from the ring, the cup flange being sufficiently flexible to yield and permit the cup to be readily withdrawn without injury to the same. When the 10 terminal cup is withdrawn the stack may drop until the next cup is in a similar position so that the cups of the stack may be successively pulled out of the apparatus. If the stack comprises only a few cups the 15 flange of a single cup at the bottom of the stack may be sufficiently strong to support the entire stack in which case it may normally rest upon the upper rib 11 of the supporting ring. In case the stack contains a 20 large number of cups so that the weight of the same is considerable, and the flange of a single cup is not sufficiently rigid to support this weight, it will be seen that the lowermost cups of the stack will be forced down 25 into the supporting ring. When this occurs, however, it will be seen that the flanges of a number of successive cups will be brought into engagement with a corresponding number of ribs 11 so that the stack of 30 cups will be supported by the combined resistance of several of the cup flanges. As shown in Fig. 2, four cup flanges are in engagement with ribs 11 so that the stack of cups is supported by the combined 35 strength of these four cup flanges. By providing a number of the ribs as shown in the drawing, the combined supporting action of enough cup flanges can be secured to provide resistance ample to sustain any 40 number of cups which it is desired to place at one time in an apparatus of this character. Ordinarily, in a device constructed as shown in the drawings, not more than three or four cup flanges will be engaged at one time when 45 a stack of one hundred cups is placed in the apparatus. When a cup is withdrawn the stack of cups will simply feed down the distance between two ribs so that ample support is at all times provided for the 50 stack and the cups can be withdrawn one at a time only. Usually there are several ribs not in supporting engagement with the cups, as shown in Fig. 2, these ribs serving to positively separate the cups if, by reason 55 of two or more of the cups sticking together, there should be any tendency for more than one cup to be withdrawn at one time.

Fig. 3 shows a slightly modified form of bracket in which the supporting ring 4 has 60 the glass tube receiving groove 8 formed at the bottom thereof, the cylindrical portion 12 of the ring extending above this groove where it will be inclosed by the lower part of the glass tube when set in the groove. In 65 this way the cylindrical portion 12 fits inside

of the glass tube and steadies the same. The ring 4 is provided with the annular ribs 11 as already described. If desired the cylindrical portion 12 of the ring may be provided with a plurality of slits 13 which 70 render the same somewhat flexible and permit the sections of the ring to be bent in or out slightly so as to permit adjustment to the exact diameter required to secure the most satisfactory movement of the cups 75 through the apparatus.

In Figs. 4 and 5 I have illustrated a modification of my apparatus in which the cup separating ribs 11 are spaced apart distances somewhat greater than the distances 80 between the flanges of successive cups in the stack. In this way all of the terminal cups will not be in direct engagement with ribs but one or more of them only will so engage ribs, which, however, will afford 85 ample support for the stack under the usual conditions of use. As shown, the ribs are so spaced that the first and fourth cup flanges are in engagement with ribs. The spacing of the cup supporting ribs a greater distance 90 apart than the cup flanges has the advantage of insuring a positive separation of the cups when one is withdrawn from the apparatus. This action is illustrated in Figs. 4 and 5; for example, assuming that it is 95 desired to remove a cup from the apparatus, the lowermost cup shown in Fig. 4 will be grasped and pulled down. A sufficient force will have to be applied to cause its flange 10 to spring over the rib 11 which is 100 supporting it, the application of this force requiring the operator to grasp or squeeze the cup rather tightly. As soon as the flange 10 slips over the rib, however, the downward pulling being no longer required, 105 the operator will automatically release the strength of his grasp upon the cup to some extent. As the cups are of somewhat yieldable material, the terminal cup will be squeezed into engagement with the next to 110 the terminal cup at the moment that its flange is passing the rib so that the next to the terminal cup will also be pulled down, the more so as it is not supported at the time by one of the ribs. When the flange of 115 the terminal cup passes the rib, however, the pressure upon it and upon the next to the terminal cup is relaxed and at about the same time the flange on the next to the terminal cup will be brought into engagement with the rib which has just been passed by the flange of the terminal cup. This rib being abruptly struck by the flange 120 of the next to the terminal cup, in effect strikes a blow thereon which loosens and separates the next to the terminal cup from the cup being withdrawn. Fig. 5 shows how the next to the terminal cup is drawn into engagement with the annular rib which formerly supported the terminal cup, the 125 130

latter being shown drawn down toward the bottom of the ring and entirely separated from the stack. In case the next to the terminal cup should be wedged in, or stuck to the cup to be withdrawn so that it was not separated upon the passing of the first rib as described, the same action is repeated each time the terminal cup is drawn past a rib so that there is practically no danger of withdrawing more than one cup at a time.

Fig. 6 shows a modified arrangement of the cup supporting ribs in which a number of ribs, four as shown, are provided in the upper part of the cup delivery orifice which are spaced apart distances equal to the distances between the cup flanges of successive cups while the lower part of the ring carries cup separating ribs spaced apart distances greater than the distances between cup flanges. In this way the stack of cups will be supported by the flanges of a plurality of successive cups as in the form of apparatus shown in Figs. 1 and 2, while if the cups stick together while being withdrawn, the spaced ribs in the lower part of the ring will serve to positively separate them in the manner described in connection with the structure of Figs. 4 and 5. Fig. 6 shows the stack being supported by two cups engaging the upper ribs while the two terminal cups have been drawn down and finally separated by the engagement of the next to the bottom cup with the first of the spaced ribs, the bottom cup being about to be withdrawn for use.

Fig. 7 shows a modified construction of cup dispensing ring in which instead of complete annular cup supporting ribs being provided, spaced rib sections 14 are employed. As shown, these rib sections each extend about one quarter of the way around the cup delivery orifice, being arranged in pairs and spaced at opposite sides of the orifice. The pairs of sections at successive levels are staggered with relation to each other so that a cup is first engaged by rib sections at opposite ends of one diameter and as it is pulled down in the rings by sections arranged at the ends of a diameter at right angles thereto. By this arrangement greater freedom of movement is allowed to the cups and cup flanges which may be distorted out of circular shape as the cups are drawn through the ring, thereby facilitating their removal. The spacing of the sections 14 vertically may be either equal to the distance between the successive cup flanges as is shown in Figs. 1 and 2, or the rib sections may be spaced as shown in Figs. 4, 5 and 6, or otherwise, as desired.

While I have illustrated and described only certain specific embodiments of my invention, it is to be understood that the invention is not limited to such embodiments.

I intend to cover every form of apparatus in which the principle of my invention is embodied.

Having thus described my invention, I claim:—

1. A cup dispensing member having an opening therethrough and having its interior surface transversely corrugated to present a plurality of supporting ledges to be engaged successively by cups in their passage through the device. 75

2. A cup dispensing member having an opening therethrough of substantially uniform diameter, and having its interior surface provided with alternate parallel ridges 80 and grooves to present a plurality of supporting ledges to be engaged successively by cups in their passage through the device.

3. A cup dispensing device comprising a supporting device for a stack of nested flanged cups permitting the withdrawal of said cups one at a time through an opening therein, said cup supporting device having its interior surface provided with alternate parallel ridges and grooves, the diameter of 85 said ridges being less than the diameter of the flanged portion of said cups, and the grooves being of greater diameter than the diameter of said flanged portion whereby the weight of said stack of nested cups will be 90 sustained in part by each of the several successive ridges. 95

4. A cup dispensing device, comprising a supporting device for a stack of nested flanged cups, permitting the withdrawal of 100 said cups one at a time through an opening therein, said cup supporting device having its interior surface provided with alternate parallel ridges and grooves, said ridges being unequally spaced apart, the diameter of 105 said ridges being less than the diameter of the flanged portion of said cups, and the grooves being of greater diameter than the diameter of said flanged portion whereby the weight of said stack of nested cups will be 110 sustained in part by each of the several successive ridges and the cups positively separated when dispensed.

5. In a cup-dispensing device, the combination of a cup supporting ring having 115 vertically spaced annular ribs projecting inwardly from the inner surface thereof, and a cup-holding tube normally closed at the upper end and removably mounted upon the said ring. 120

6. In a cup-dispensing device, the combination of a cup supporting ring having a plurality of spaced annular ribs extending inwardly from the inner surface thereof, said ring having an annular seat thereon, 125 and a glass cup-receiving tube closed at the upper end and removably supported upon said seat.

7. In a cup-dispensing device, the combination with a supporting device for a 130

4

stack of nested cups, permitting the withdrawal of said cups one at a time through an orifice therein, said cup-supporting device having a plurality of vertically spaced 5 cup engaging ribs, successive ribs being adapted to be engaged by successive cups, sufficient ribs being brought into engagement by the weight of the stack of cups to support said weight.

10 8. In a cup-dispensing device, the combination with a supporting device for a stack of nested flanged cups; having a delivery opening therethrough through which a portion of the terminal cup is adapted to project, said support having a plurality of inwardly projecting vertically spaced ribs

about said opening such ribs adapted to engage the flanges of the terminal cups, the weight of the stack of cups causing the cup flanges of a sufficient number of the lower 20 terminal cups of the stack to be brought into engagement with the successive supporting ribs to provide adequate support for the entire stack.

In witness whereof, I have hereunto set 25 my hand in the presence of two subscribing witnesses.

LAWRENCE W. LUELLEN.
